CLAIM

The ornamental design for a wheel loader, as shown and
described.

DESCRIPTION

FIG. 1 is a front view of a wheel loader of our new design;
FIG. 2 is a rear view thereof, with the bucket in a lowered
configuration;

FIG. 3 is a top view thereof, the elements depicted in broken
lines form no part of the claimed design;

FIG. 4 is a right-side view thereof;

FIG. 5 is a left, rear perspective view thereof, with the bucket
in a lowered configuration; and,

FIG. 6 is a left, rear perspective view thereof, with the bucket
in a raised configuration.
